DESCRIPTION

U.S. PATENT DOCUMENTS

FIG. 1 is a top, front, and right side perspective view of our new design for a tabletop housing for a video monitor and peripherals; and,

D. 216,712 * 3/1970 Cooper D6/422
D. 360,545 * 7/1995 Lechman D6/422

FIG. 2 is a top, front and right side perspective view of our new design with the tabletop open.

The broken lines are shown in the views for illustrative purposes only and form no part of the claimed design.
